GASEOUS DISCHARGE DEVICE

Richard M. Somers, Orange, N. J., assignor to
 Thomas A. Edison, Incorporated, West Orange,
 N. J., a corporation of New Jersey

Application March 20, 1935, Serial No. 11,919

5 Claims. (Cl. 176—122)

This invention relates to electric discharge devices, and more particularly to those of the gaseous type—i. e., containing an inert gas or mixture of gases and/or a metal adapted to form a vapor within the device during its operation. Further the invention relates to such devices wherein are employed a plurality of anodes relatively near to each other and relatively distant from the cathode as is common practise in positive column devices when the discharge is to be maintained by an alternating current supply.

The operation of such devices is usually such that large potential differences exist between the anodes. In the absence of any preventive measure, these potential differences may cause "arc-backs" between the anodes—i. e., disruptive discharges from one anode or its connecting lead to the other anode or lead, which discharges impair the operation of the device and usually completely ruin it. Customarily these arc-backs are prevented by arranging the anodes in individual stems, constrictions, or the like, or by suitably interposing between the anodes shields of metal or of glass or other refractory material. These preventive measures function by increasing the length and/or the circuitousness of the anode-to-anode path within the device. While they are effective if appropriately carried out, they obviously materially increase the structural complexity and cost of the device.

It is an object of my invention to provide a simplified device of the class described wherein arc-backs are efficiently prevented.

It is another object to provide a device of the class described, characterized in operation by freedom from arc-backs, wherein the anodes are placed very close to one another without the interposition of shields or the like between the anodes.

Another object is the provision of improved means for preventing arc-backs in devices of the class described.

Still another object is the provision of improved anode supporting and connecting structures and arrangements appropriate to the prevention of arc-backs.

Yet another object is the provision of improved methods of assembling the anode system in a device of the class described.

Other and allied objects will more fully appear from the following description and the appended claims.

In the description reference is had to the accompanying drawings, of which:

Figure 1 is a partly cross-sectional and partly

schematic view of a discharge device according to my invention, together with a typical associated circuit;

Figure 1a is an enlarged cross-sectional view of the anode portion of Figure 1, which comprises one embodiment of the first species of my invention;

Figures 2 and 3 are cross-sectional views of two variations of the portion of Figure 1 which is shown as Figure 1a, illustrating as many alternative embodiments of the first species, Figure 3 illustrating the preferred among the three illustrated embodiments of this species;

Figure 4 is a cross-sectional view, of similar scope as to contents to the three preceding figures, but illustrating a second species of my invention; and

Figures 5 and 6 are cross-sectional views of two embodiments of the third species of my invention, Figure 6 illustrating the preferred between the embodiments of this third species.

It is well understood that the prevention of arc-backs in any case is facilitated by the use of anodes of carbon or other high work function material. I have found that with such anodes, close together and unshielded from each other—i. e., mutually exposed—arc-backs will be confined to those occurring between an anode and the electrical connecting means for the other anode; and further, that arc-backs will not occur at all below a critical anode-to-anode voltage, provided the means for making electrical connection to the anodes are suitably constructed and arranged. The critical voltage abovementioned will vary according to various parameters of the device, particularly with the gas pressure, tending to lower as the pressure is raised. I have found, however, that for typical low pressure tubes, e. g., containing gas at a pressure of 10 millimeters of mercury or less—the critical voltage may be established at a value well in excess of 300 volts A. C. (420 volts peak or D. C.); for a typical tube with a gas pressure of 4 millimeters of mercury it may be of the order of 500 volts A. C. (700 volts peak or D. C.). Either of these figures is obviously well in excess of the voltage required to exist between anodes in efficient devices adapted for various uses, among which may be particularly mentioned that of illumination.

Broadly and principally, the structure and arrangement which I employ in association with the connecting means for the anodes is one wherein each of these means is surrounded, at all points longitudinally thereof between the en-

velope and a point intermediate the extremities of the respective anode, by one or more tubes formed of refractory insulating material. These tubes are so disposed as to lengthen the shortest 5 arcing paths, from the anodes to the connecting means for the respectively opposite anodes, by annular passages of negligible thicknesses, or of thicknesses which are at most very small fractions of their lengths. These passages are 10 formed between the refractory insulating tubes and portions of the anodes and/or between portions of different tubes. Their efficacy in suppressing arc-backs probably results from the development of space charges on the passage walls. 15 It may here be noted that I employ the term "passage" as denoting the space, between two mutually adjacent members, through which an arc-back might travel; and that this term is still employed although the members may be in actual 20 contact with each other and the space therefore vanishingly small, since such a space may still under certain circumstances provide an arcing path or passage. It will further be understood that the term "tube" and its derivatives are intended 25 to denote broadly cross-sectional continuity, and not necessarily true circularity, and that the term "annular" as employed herein is likewise not intended to be limited to true circularity. The circular formation is usually most 30 convenient, however, and has been employed in illustration herein.

The particular features which are characteristic of my invention are set forth in detail hereinafter. Reference is first invited, however, to 35 Figure 1, wherein I illustrate a typical device and associated circuit.

In the figure will be seen the tube 1 having the glass or other refractory envelope 2, the space 2' within the envelope having been evacuated of 40 air and containing an inert gas, or combination of gases, and/or if desired a small quantity of metal adapted for vaporization upon heating of the device. The elements of the tube are the cathode 3, the anodes 4a and 4b (hereinafter 45 more fully referred to), and the auxiliary starting electrode 5. The cathode 3 is of the thermionic type, and by way of example has been illustrated as a folded filament which may be coated with suitable oxides or the like to increase 50 its emission. The anodes 4a and 4b are located near the opposite end of the tube from the cathode 3. The starting electrode 5 may be a conductive ring surrounding and in slight spaced 55 relationship to the cathode 3.

The discharge current for the device may be obtained from an alternating current line through the transformer 6, which by way of illustration has been shown as an auto-transformer. One side of the line is connected 60 through the "on-off" switch 9' to the primary terminal 6p of the transformer, while the other side of the line is connected selectively to the primary terminals 6p', 6p'' and 6p''' through the selecting switch 9''. The transformer may 65 have the extreme secondary terminals 6a and 6b and the secondary center-tap 6c; the first two are connected respectively to the anodes 4a and 4b through the ballast resistances or lamps 8a and 8b, while the center-tap 6c is connected to 70 the cathode 3 through the inductance coil or choke 10. A tertiary winding 7 forming a part of the transformer 6 may be connected across the extremities of the filament or cathode 3 for heating the same.

In a system such as I have illustrated it is

usually necessary to initiate the gas discharge by a momentary discharge at relatively high voltage. While a variety of means for producing such a transient discharge may be employed, I have by way of illustration shown a system certain features of which have been described and claimed in my copending application Serial No. 716,038, filed March 17, 1934, and on which Letters Patent No. 2,013,974 were issued on September 10, 1935. Briefly this system may be constructed by connecting the starting electrode 5 through a circuit-breaking switch 12 to a tap 6d located on the transformer secondary to one side of the center-tap 6c. The switch 12 comprises a spring arm 12' carrying the armature 12'' and the contact 12a, the arm being biased normally to press the contact 12a against a stationary contact 12b—i. e., to maintain the switch closed. The armature 12'' is positioned in the field of attraction of the core 10' of choke 10, and is adapted to be moved toward the core 10', and thus to open the switch 12, when the attraction of the core 10' exceeds a certain minimum. As soon as the primary "on-off" switch 9' is closed 10 heating of the cathode 3 is initiated and the terminals 6a and 6b are invested with alternating potential differences from the center-tap 6c. As soon as the cathode has been slightly heated a small gaseous discharge will take place every alternate half-cycle from the starting electrode 5 to the cathode. As the temperature of the cathode rises the magnitude of this discharge increases; and when the discharge attains a magnitude correspondent to substantially normal cathode operating temperature the attendant 20 current through the choke 10 causes the core 10' to attract the armature 12'' and open the switch 12, which has been adjusted to this end. The sudden breaking of current flow through the choke causes the appearance across the choke of 25 a transient, which by virtue of the circuit position of the choke is automatically applied between the anodes on the one hand and the cathode on the other. This transient produces a transient discharge from anodes to cathode, 30 which ionizes the gas within the device and continues as a normal anode-cathode gaseous discharge by virtue of the potentials from the secondary terminals. If vaporizable metal such as 35 mercury is included in the device in addition to an inert gas such as krypton, the gaseous discharge will serve to vaporize the metal, whereupon the normal discharge may transfer itself from the gas to the vapor as a medium.

It will of course be understood that throughout the normal discharge in this system the positive end of the discharge column will shift back and forth between the two anodes 4a and 4b, each anode being inoperative during alternate substantial half cycles. It will further be appreciated that at the peak of each half cycle the potential difference between the anodes rises to almost the peak voltage difference between the secondary terminals 6a and 6b; this voltage rise is that which tends to produce arc-backs.

The general operation of the typical system having been thus outlined, particular attention may be directed to the anodes 4a and 4b and their supporting and connecting means, a particular structure and arrangement of which is illustrated in Figure 1, and in enlarged cross-sectional form in Figure 1a, with variations in succeeding figures. In general all the structures are adapted for manufacture by automatic ma-

chines and do not require laborious and costly hand-work.

In Figure 1a the anodes 4a and 4b are seen in the form of short round rods of carbon having axes mutually parallel and in line with the direction of the discharge column. Illustratively the anodes may be approximately $\frac{1}{4}$ inch in diameter, 1 inch long, and spaced apart by slightly more than $\frac{1}{8}$ inch (i. e., having slightly greater than a $\frac{1}{8}$ inch center separation). As the length of the positive discharge column may be considered to be 5 inches or greater, it will be seen that the anodes are relatively closely adjacent each other and the cathode relatively distant therefrom. The anodes are supported and electrically contacted by the rods 42a and 42b. These rods are of conductive material—desirably of tungsten—and are held in appropriate mutually spaced and substantially parallel relationship in the stem or press 2" of the envelope 1. In assembling the illustrated anode system there are first formed around intermediate portions of the rods 42a and 42b the elongated glass or other refractory insulating beads 44a and 44b; these beaded rods are then sealed into the stem 2" so that upon assembly of the stem to the envelope the beads 44a and 44b will extend inwardly of the envelope. The anodes are next assembled on the rods 44a and 44b, as below more fully described, and the stem 2" finally sealed in its place at the end of the envelope, as along the line 2''' of Figure 1.

For assembling the anodes on the rods 42a and 42b the anodes are provided with the axial holes 41a and 41b, which may extend inwardly from one end of each for a major fraction of the anode length. These holes are adapted frictionally to engage the extremities of the rods 42a and 42b, these extremities 42' having been peripherally roughened—for example as a result of having been cut off by pliers—as clearly illustrated for example in Figure 2. In Figure 1a the anodes are also shown as provided with the central apertures 43a and 43b of larger diameter than the holes 41a and 41b but extending a shorter distance inwardly from the same end; in assembling the anodes on the rods the anodes are pushed onto the rods until the bases of the apertures 43a and 43b have bottomed against the extremities of the beads 44a and 44b. These aperture bases are preferably slightly rounded or bevelled so as to tend to fit the ends of the beads.

In this structure it will be seen that the rods 42a and 42b are completely surrounded with the tubular beads 44a and 44b from the stem 2" to the bases of the apertures 43a and 43b, so that the only portion of either rod which is connected by any form of passage with the space 2' within the envelope is the very small or infinitesimal portion between the respective aperture base and the end of the respective bead. The passage by which this rod portion is connected with the space 2' is principally the very thin annular passage 45a formed between the bead 44a and the wall of the aperture 43a, or the like passage formed between the bead 44b and the wall of the aperture 43b, as the case may be. (Additionally, of course, each passage includes the short, cross-sectionally rounded or bevelled, thin space between the base of the respective aperture and the end of the respective bead.) These passages become included in the arcing paths to the respective rods from the respectively opposite anodes, which paths are thus lengthened by these passages.

Generally speaking, the efficacy of the thin annular passages upon which I largely rely in suppressing arc-backs is a function of the passage length and an inverse function of the passage thickness; thus for example in the particular embodiment of Figure 1a it is desirable that at least the end portions of the beads 44a and 44b be always as nearly perfectly circular as practicable, and that the diameter of the apertures 43a and 43b be as small as may be depended upon in production to admit the bead end portions. A further characteristic of these annular passages, as illustrated not only in the passages of Figure 1a but also in all the other annular passages of negligible thickness in all of the embodiments, is that their length is at least of the order of the residual length of the shortest arcing path, or of the minimum spacing of either anode from the opposite rod. While I consider this characteristic advantageous, I do not wish to limit my invention thereby excepting as so specifically claimed.

In succeeding figures I show several variations of the anode assembly. In each case the rods 42a and 42b may be provided with the roughened end peripheries 42' to provide frictional engagement with the holes 41a and 41b in the anodes; but the apertures 43a and 43b in the anodes, and the beading 44a and 44b on the rods, are retained, eliminated or replaced as specifically described for each variation.

Figure 2 illustrates an alternative embodiment of the same species of my invention as Figure 1a. In Figure 2 the rods 42a and 42b are surrounded for part of their length by the small glass or other refractory insulating tubes 46a and 46b; these tubes may have an internal diameter just large enough to slip over the rods. The rods are assembled into the stem 2" with the tubes 46a and 46b partially extending into the stem material, so that both rod and tube are sealed into the stem. Instead of the apertures 43a and 43b in the anodes there are provided the similarly placed apertures 47a and 47b; these have square rather than rounded or bevelled bases, and are of a diameter appropriate snugly to fit over the tubes 46a and 46b. The anodes are slipped on the rods until the bases of apertures 47a and 47b bottom against the ends of tubes 46a and 46b. This embodiment is generally quite similar to that of Figure 1a, but the annular passages, herein designated as 60a and 60b, are more easily held to a negligible thickness, by virtue of the naturally more perfect periphery of a separately formed tube than of a bead formed on the rod. An additional small distinction is found in the nature of the space between the aperture base and the end of the insulating tube; this is now a thin, short, washer-like passage in series with and at complete right angles to the respective annular passage 60a or 60b. This right angular relationship affords a measure of additional security against arc-backs, which may in general be considered reluctant to follow a sharply angled passage.

Figure 3 I have termed the preferred embodiment of the first species of my invention because it adds at the outer extremity of each annular passage a thin, washer-like passage in series with and at right angles to the annular passage. This washer-like passage is formed between the end of each anode and an adjacent refractory insulating member, and may comprise an addition to either of the thus-far illustrated embodiments. I have illustrated it in Figure 3 as the structure of

Figure 1a with the addition of glass or other refractory insulating tubes 37a and 37b sealed into the stem 2" around and at the same time as the beads 44a and 44b. These tubes may be of slightly larger internal diameter than will dependably admit the beads, though of course of smaller external diameter than the anodes; they are of a length appropriate to come into substantial abutment against the anodes when the latter are assembled on the rods as set forth in the description of Figure 1a above. Thus the thin, washer-like passages are formed between the anodes and the respective extremities of tubes 37a and 37b, and have been designated in Figure 15 3 as 61a and 61b.

In Figure 4 I have illustrated a structure which I term the second species of my invention. I again surround the rods with tubes of refractory insulating material sealed into the stem 20 coincidentally with the rods and extending to points intermediate the extremities of the anodes; but in this instance I employ tubes 48a and 48b which are of an internal diameter appropriate to be fairly snugly fitted by the periphery of the 25 anodes, which are slipped onto the rods sufficiently to extend for a distance within the tubes. Annular passages 62a and 62b of negligible thickness are thus formed between the outer walls of the anodes and the inner walls of the respective 30 tubes.

The arrangement of Figure 4 provides no sharp angles to be turned by an arc-back, but offers, in addition to the annular passages of negligible thickness, a different impediment to arc-backs. 35 This may be best understood by noting that in each of the embodiments of the first species the path of an arc-back, between one anode and its terminal point on the rod of the respectively opposite anode, traverses a space between the two 40 anode structures which is removed from the cathode (and hence from the positive discharge column) at least as far as the further extremities of the anodes. In Figure 4, however, the path of a possible arc-back traverses a space relatively nearer the cathode and hence nearer the 45 positive discharge column, in which space an arc-back will take place only with greater difficulty.

It is well known that when a glass tube is held tightly at two points—e. g., at or near each of its 50 respective extremities—strains will be imparted to it unless the holding structure is of a high degree of precision. When glass is employed as the refractory insulating material, such strains are sometimes set up in the structures above 55 described, and these strains tend to be augmented by the great heating of the anodes which is a necessary incident to evacuation of the complete discharge device. For this reason I believe most advantageous the third species of my invention, which I have illustrated in two embodiments, neither involving tight holding of a 60 refractory insulating tube at more than one extremity. The surrounding of the rods with tubular refractory insulating means from stem to 65 points intermediate the anode extremities is of course maintained, but in a slightly more elaborate form.

In the embodiment of Figure 5 the anodes, adapted to be held on the rods in the usual manner, are provided with apertures 50a and 50b, generally similar to apertures 47a and 47b of Figure 2 but preferably extending for a relatively greater distance into the anodes. Into the stem 2" are sealed the rods 42a and 42b and there- 70 around the glass or other refractory insulating

tubes 51a and 51b, having an internal diameter equal to or slightly exceeding the diameter of the apertures 50a and 50b, and extending inwardly from the stem by a length preferably still greater than the length of apertures 50a and 50b. Glass 5 or other refractory insulating tubes 49a and 49b of internal diameter to fit somewhat loosely over the rods 42a and 42b and of external diameter slightly less than that of apertures 50a and 50b, are slipped over the rods. Finally the anodes are 10 assembled on the rods in longitudinal position affording a substantially snug longitudinal fit for the tubes 49a and 49b between the stem 2" and the bases of the anode apertures 50a and 50b; preferably the lengths are so apportioned that the 15 anodes are then but slightly spaced from the tubes 51a and 51b.

In this embodiment two thin annular passages exist in each anode assembly through which an arc-back might pass to the rod—e. g., the passage 20 63a between the tube 49a and the anode 4a, and the passage 64a between the same tube and the tube 51a, each in series with a respective thin, washer-like passage formed at the respective end of the tube 49a. In addition there is a common 25 thin washer-like passage 65a in series with both of the annular passages 63a and 64a. The finite, though small, mean thickness of passage 63a is compensated for by somewhat greater length than previously illustrated annular passages, and the 30 still greater mean thickness of passage 64a by still greater length.

In Figure 5 the inner insulating tube—e. g., 35 49a—is not held at either of its extremities. No objection obtains against holding such an inner tube at one extremity; and in Figure 6 I show a preferred embodiment of this third species in which an inner tube is so held. The anodes in this figure are provided with the apertures 47a and 47b (as in Figure 2), and into these holes are 40 respectively fitted, as snugly as practicable, glass or other refractory insulating tubes 52a and 52b of internal diameter well exceeding the diameter of rods 42a and 42b. Glass or other refractory insulating tubes 53a and 53b, of slightly greater 45 internal diameter than the apertures 47a and 47b, are sealed into the stem 2" as were the tubes 51a and 51b of Figure 5; the tubes 53a and 53b extend inwardly from the stem 2" by a length desirably greater than that of apertures 47a and 50 47b. While the rods 42a and 42b may be sealed into the stem 2" as in Figure 5, I prefer first to provide them with short beads 54a and 54b which after sealing extend somewhat inwardly from the stem. The anodes, with tubes 52a and 52b respectively secured therein, are assembled on the rods so that the outer extremities of the tubes 52a and 52b extend into the annular spacings between the beads 54a and 54b and the tubes 53a and 53b; these extremities may be slightly spaced, however, 60 from the stem 2", and are not in contact any more than loosely with the beads 54a and 54b. While the tubes 53a and 53b need only extend from the stem by the extent above mentioned, they may if desired extend to a very slight spacing from the 65 anodes, and have been so illustrated.

In this embodiment the annular passages between the inner tubes (52a and 52b) and the anodes are of course of negligible thickness, being similar to the passages 60a and 60b of Figure 2 70 and having been designated as 60a' and 60b'; they are of course in series with the washer-like passages of negligible thickness formed at the inward extremities of the inner tubes. The annular passages between inner and outer tubes, desig- 75

nated as 66a and 66b, are of finite thickness but of greater length than passages 60a' and 60b'; furthermore these passages 66a and 66b are respectively in series with the short, thin annular 5 passages 67a and 67b formed between the inner tubes and the respective beads 54a and 54b, the mutual arrangement of passages 66a and 67a (or 66b and 67b) being such as to force a possible arc-back therethrough to execute a complete 10 reversal of direction in the very small space at the end of the inner tube. Finally, if the outer tubes 53a and 53b are extended, as illustrated, into very slight spacing from the anodes, they form with the anodes the thin, washer-like passages 65a' and 15 65b', in series with both the passages 60a' and 66a (or both 60b' and 66b) and at right angles thereto.

It will be understood that in the appended 20 claims, some of them generic to the three species of my invention and others specific to individual 25 species, I intend to claim my invention as broadly as the state of the art will permit.

The term "gas" and its derivatives, as used in the following claims and in broader contexts in the description, are intended to refer to one or 25 more gases and/or one or more metal vapors. Also the term "refractory insulating" as used in the specification and claims, is intended to refer to materials such as glasses, alumina, magnesium 30 oxide, natural rocks, etc.

30 I claim:—

1. In a gaseous discharge device having an envelope, a conductive rod passing through said envelope; an anode mounted on said rod; a refractory insulating bead about said rod and sealed to said envelope; and a refractory insulating tube surrounding said bead and rod and entering said anode.

2. In a gaseous discharge device having an envelope, a conductive rod passing through said envelope; an anode mounted on said rod; tubular refractory insulating means spacedly surrounding said rod and extending from within said anode toward said envelope; a further tubular refractory insulating means closely surrounding 45 said first means and sealed to said envelope; and

a refractory insulating bead about said rod, sealed to said envelope and entering said first means.

3. In a gaseous discharge device, an envelope having a stem; a conductive rod passing through said stem and extending therefrom inwardly of 5 said envelope; an anode entered by said rod, an aperture being provided in the outward extremity of said anode about said rod; tubular refractory insulating means spacedly surrounding said rod and extending from adjacent the base of 10 said aperture toward said stem; a further tubular refractory insulating means surrounding said first mentioned tubular means, with at most relatively small spacing therefrom, sealed into said stem, and extending therefrom inwardly by a 15 substantial distance; and a refractory insulating bead about said rod, sealed into said stem, and extending therefrom for a distance inwardly of 20 said first mentioned tubular means.

4. In a gaseous discharge device, an envelope 25 and therein a pair of mutually exposed and closely adjacent anodes; conductive rods entering said anodes respectively and passing through said envelope; and refractory insulating means, surrounding each of said rods at all points longitudinally thereof between said envelope and a point intermediate the extremities of the respective said anode, for lengthening the shortest 30 anode-to-rod arcing paths by thin annular passages of lengths at least of the order of the residual lengths of said paths.

5. In a gaseous discharge device, an envelope 35 and therein a pair of mutually exposed and closely adjacent anodes, conductive rods entering said anodes respectively and passing through said envelope, and tubular refractory insulating means surrounding each of said rods at all points longitudinally thereof between said envelope and a point intermediate the extremities of the respective said anode, the portions of said means 40 co-extensive with said anodes forming therewith very thin, annular arcing passages each having a length at least of the order of the shortest path from its exposed extremity to the respectively 45 opposite anode.

RICHARD M. SOMERS.
